Inventor:

E. Goddard

United States Patent Office.

EMERSON GODDARD, OF BROOKLYN, NEW YORK, ASSIGNOR TO E. S RENWICK, OF NEW YORK CITY.

Design No. 2,912, dated February 4, 1868.

DESIGN FOR A PISTOL-BARREL.

The Schedule referred to in these Letters Patent and making part of the same.

TO ALL WHOM IT MAY CONCERN:

Be it known that I, EMERSON GODDARD, of the city of Brooklyn, and State of New York, have invented or produced a new and original shape or configuration of the article of manufacture known as a Pistol-Barrel; and that the following, taken in connection with the accompanying drawing, is a full, clear, and exact description and specification of the same.

The peculiarity of the pistol-barrel is that the corners are chamfered off or fluted, as at α α α α in the drawing, and the configuration of the exterior is the same from end to end, except at the projection b , by which the barrel is connected with the lock-frame or stock, which projection is not seen when the barrel is connected with its stock.

A barrel of this configuration is adapted especially for use in a "double-header" pistol, where the position of the ends of the barrel relatively to the recoil-shield is reversed, because such a barrel, although broader than the stock, does not look heavy, and presents the same appearance to the eye, whichever end be forward.

What I claim and desire to secure by Letters Patent, is—

The new and original shape or configuration of the article of manufacture known as a pistol-barrel, as hereinbefore set forth, and as represented in the accompanying drawing.

In testimony whereof I have hereto set my hand, this 5th day of October, A. D. 1867.

Witnesses:
